UNITED STATES PATENT OFFICE.

A. RENSSELAER SPROUT, OF PICTURE ROCKS, PENNSYLVANIA.

MACHINE FOR BENDING AND SCORING HOOPS.

SPECIFICATION forming part of Letters Patent No. 293,917, dated February 19, 1884.

Application filed July 7, 1883. (No model.)

To all whom it may concern:

Be it known that I, A. RENSSELAER SPROUT, a citizen of the United States, residing at Picture Rocks, in the county of Lycoming and State of Pennsylvania, have invented certain new and useful Improvements in Machines for Bending and Scoring Hoops, of which the following is a specification, reference being had therein to the accompanying drawings.

10 My invention relates to a machine for scoring and bending wood hoops such as are used for barrels, kegs, and the like.

The construction and the operation of the machine will first be described, and the invention then designated in the claims.

In the drawings hereto annexed, Figure 1 is a side elevation of the machine. Fig. 2 is a central vertical section of all the parts except the wheels, which latter are not sec- 20 tioned.

The letters A and A' designate the side standards, which are connected together at the upper ends by a cross-bar, B. A shaft, C, has bearing in each standard. A scoring-wheel, C', is mounted on one end of the shaft, and a gear-wheel, d, on the shaft, between its bearings. The scoring-wheel has on its face teeth e, having sharp edges, three rows of these teeth occupying the width of the face, 25 leaving a space, f, between each row. The drive-shaft G also has bearing in the standards, and carries a pinion, h, which meshes with the gear-wheel d. A pulley, G', is to receive a belt for imparting motion to the machine. A flanged wheel, I, having a smooth face, is on the end of a shaft, I', which is mounted in a pivoted arm, I². The flanged smooth-faced wheel is directly above the scoring-wheel, and normally its smooth face may 30 be in contact with the teeth of the scoring-wheel. One end of the arm I² is pivoted at k to the standard A', and the other end projects through a vertical slot, l, in the standard A. By this construction the wheel I may rotate, 35 and may rise and fall, because its shaft is carried on a pivoted arm.

The particular construction here shown may be varied, and yet produce the same result. A spring, m, is interposed between the free 50 end of the pivoted arm and the upper cross-bar, B, and serves to depress the arm, and thereby cause the wheel to exert a pressure.

Other means than a spring may be employed to give the desired pressure.

On the outer side of the standard A a 55 curved bending-plate, N, is attached. It curves about the rear side of the scoring-wheel, and its upper end has position just above the top of the scoring-wheel. A guide bracket or plate, p, is attached to the stand- 60 ard at the front side and on a plane even with the top of the scoring-wheel, and serves to direct a straight hoop-splint between the scoring and flanged pressure-wheel, as indicated by broken lines at q in Fig. 1. 65

The hoop-splints to be operated upon by this machine may be made from timber of any size. They are first properly shaped, and then steamed, and while hot are passed through this machine—that is, passed endwise between 70 the scoring-wheel and flanged wheel—and are formed circular by the curved bending-plate. The scoring-wheel teeth have sharp edges, which cut crosswise of the wood fibers of the hoop, and also compress or in some measure 75 "upset" the said cut ends of the fibers. This process has the effect to crimp or shorten one face or side of the splint, which face becomes the inner side of the hoop when the splint is subsequently formed or bent circular. The smooth 80 wheel I has an up-and-down play which describes an arc of a circle of which the pivot k is the center. This particular movement provides at once for two ends—namely, the pressure-wheel may yield to accommodate variations 85 in thickness of the hoop-splint, and also it thereby is adapted for flat hoops which are thicker at one edge than the other, it being understood that in such case the thin edge of the hoop-splint will be next to the flange of 90 the wheel.

Having described my invention, I claim—

1. In a machine for bending hoops, the combination of a scoring-wheel, C', provided with cutting-teeth, a smooth wheel, I, adjoining the scoring-wheel, means to cause the smooth wheel to press against the scoring-wheel, a guide-bracket, p, at the front side of the scoring-wheel, and a bending-plate, N, which curves about the rear side of the scoring-wheel, as set forth. 95

2. In a machine for bending hoops, the combination of a scoring-wheel, C', provided with cutting-teeth, a shaft, I', having one end piv- 100

oted, whereby the other end may have play or movement, a smooth wheel, I, on the movable end and adjoining the scoring-wheel, means to cause the smooth wheel to press against the 5 scoring-wheel, and means at the rear side of the scoring-wheel to bend the hoop, as set forth.

3. In a machine for bending hoops, the combination of a scoring-wheel, C, provided with 10 cutting-teeth, an arm, T², pivoted at one end,

a shaft, I', mounted on said arm, a smooth wheel, I, on the movable end of the shaft, and means to cause the smooth wheel to press against the scoring-wheel, as set forth.

In testimony whereof I affix my signature in 15 presence of two witnesses.

A. RENSSELAER SPROUT.
